UNITED STATES PATENT OFFICE

AUGUST J. KOEPSELL, OF MAYVILLE, WISCONSIN

SHAKING GRATE FOR FURNACES

Application filed August 28, 1928. Serial No. 302,563.

This invention relates to furnace grates and particularly to those grates in which oscillatory grate bars are used adapted to be oscillated for the purpose of shaking up the ashes and cinders on the grate, discharging the ashes and permitting the passage of air through the fire bed.

One of the objects of the present invention is to provide a grate, the principle of which 10 may be applied either to large or small grates and which is so constructed that either in large or small grates the proper proportionate area for the passage of air and the proper proportionate area for the passage of 15 ashes may be secured.

As further object is to provide a grate of this kind which may be arranged so as to merely shake the fire bed and discharge the fine ashes therefrom or which may be dumped 20 and in this connection to provide means whereby the grate may be held from accidental dumping while shaking, this means being shiftable to permit the rotation of the grate bars to a dumping position.

Other objects will appear in the course of the following description.

My invention is illustrated in the accompanying drawings wherein—

Figure 1 is a top plan view of one form of my improved grate;

Figure 2 is a front elevation of the grate showing in dotted lines the position of the grate bars and showing in section a part of the grate frame and the support therefor in section;

Figure 3 is a top plan view of a modified form of grate embodying the same principle;

Figure 4 is a transverse section through this grate;

Figure 5 is a fragmentary top plan view of another embodiment of grate made under my system and showing a modification of the locking means therefor;

Figure 6 is an elevation of the locking or limiting means, the shafts being in section; and

Figure 7 is a transverse sectional view through the grate shown in Fig. 5.

In Figs. 1 and 2, I have illustrated a grate for a relatively large fire pot and ash pit and

in this drawing, 10 designates the rim of the grate flanged at 11 so that it may be supported upon the inwardly extending flange 12 of the fire box and above the ash pit 13. The rim 10 is preferably a split rim, that is, the rim is formed in two sections, and the opposite inner margins of the rim are formed with a plurality of inwardly extending lugs 14. Extending through the rim or as illustrated having bearing against the under faces of the 55 rim, are a plurality of shafts 15 and 16, the numeral 16 designating the middle shaft of the three shafts illustrated. Each shaft 15 carries upon it a shaking grate section 17. This grate section as illustrated has the shaft 60 15 formed integral with it, as for instance as by casting and projecting from opposite ends of the grate section.

Each grate section 17 is formed with a plurality of openings 18, the openings at the 65 middle of the grate section being relatively long and the openings at the end being relatively short, so that the outer ends of these openings are disposed on a curved line conforming to the curvature of the outer margin 70 of the grate section. The outer margin or edge of the grate section 17 is provided with outwardly projecting lugs 19 which extend into the spaces between the lugs 14. In other words, the rim 10 and the 75 grate sections 17 are interdigitated. The inner margin of each grate section 17 is also formed with a plurality of inwardly projecting lugs 20 disposed approximately opposite the lugs 19. The middle shaft is cast with 80 or carries upon it the middle grate section 21 which is formed in its lateral margin with the laterally projecting lugs 22 which interdigitate with the lugs 20 and with lugs 85 formed upon the rim 10 beyond the ends of the grate sections 17. The middle of the grate section 21 is preferably formed with a series of openings 23. The cross section of the grate sections or grate bars 17 and 21 shows, as illustrated in Fig. 2, that these 90 bars or sections are slightly rounded at their ends and that they have a depth of approximately four inches though this depth may be reduced to three inches under some circumstances, as will hereafter appear. The three 95

100

shafts 15 and 16 are formed, each at one end with means whereby a crank may be applied thereby and whereby these grate bars 17 and 21 may be rocked or oscillated independently of each other.

These grate bars may also be turned into a vertical position for dumping the fire pot, but in order to prevent the bars from being turned to this dumped position accidentally, I provide the like ends of all of the shafts 15 and 16 with the outwardly projecting lugs or stops 24, see Fig. 2, there being two diametrically opposed stops or lugs on each shaft. Mounted in conjunction with the shafts is a sliding bar 25 carried upon any suitable guide, as for instance, the cross bar 26; this locking bar 25 being cut away at three points as at 27 and one end wall of this cut away portion is formed with an inwardly projecting lug or stop 28. This locking bar 25 is connected to any suitable means whereby it may be shifted into or out of operative position, as for instance the lever 29. When the locking bar is in the position shown in Fig. 2, the lugs 28 limit the oscillation of any one of the shafts 15 or 16 approximately to a quarter turn from the normal in one direction or the other. When, however, the locking bar is drawn laterally to the left in Fig. 2 the stops 28 are drawn out of the path of movement of the lugs 24 and the grate bars may be rotated through a half or a whole rotation. When the grate bars are turned so that they are vertical they are in dumping position and the clinkers, ashes, and unburned coal on the grate may be discharged into the ash pit. When the locking bar is in position, however, it limits the rotation of the several grate bars to approximately a quarter turn from normal position, and the fire bed is merely shaken.

It will be noted that the lateral faces of the grate bars are so formed that clinkers or unburned coal are little likely to jam between the grate bars. This reduces the chance of breaking the teeth or lugs on the grate bars and reduces the likelihood of jamming, which is present in the ordinary grate.

This is particularly true by reason of the fact that the grate bars are independently oscillatable. This type of grate is very simple and has no gearing whatsoever and is therefore convenient to operate. The form, shape, and arrangement of one grate section relative to the next grate section is such that the pinching of clinkers between the grate sections is impossible. It will be seen that inasmuch as the grate rim or frame is made in two sections and these sections are disposed so that the line of separation is transverse to the grate bars, it is an easy matter to pull off these sections from the grate bars and thus these sections and the grate bars may be entirely separated from each other and the

grate readily taken down and replaced without taking the furnace apart.

In order to avoid the weakening of the extremities of the grate sections or bars, 17, these sections or bars terminate short of the grate sections 21 and the rim 10 is formed with openings 30 through which ashes will sift.

In Fig. 5 I illustrate another form of grate adapted for a different sized fire pot but embodying the same principle as in the grate previously described. In this case the rim 31 is also circular in form and provided with a plurality of inwardly projecting lugs 32 on opposite sides of the rim, these lugs at the middle of the rim being relatively long, and at the ends of the rim being relatively short. Each of these lugs, as illustrated in Fig. 7, is cut away at its end face as at 33. Rotatably mounted on the rim 31 are two longitudinally extending shafts 34 which extend beyond the cut away portions 33 of the lugs 32, these shafts carrying the laterally projecting lugs 35 constituting grate bars. The lugs 35 on one shaft are in staggered and interdigitating relation to the lugs 35 on the adjacent shaft as shown in Fig. 5, and the lugs on each shaft are of such length that they extend nearly to the adjacent shaft.

Inasmuch as the lugs or grate bars on one shaft are in staggered relation to the lugs or bars on the other shaft, it follows that the lugs 32 on one side of the rim are in staggered relation to the lugs on the other side of the rim. The ends of the grate bars or lugs 35 are rounded as shown in Fig. 7. Preferably, these lugs or bars 35 are four inches in depth and are of such length that when the bars are turned into vertical position, the space between the bars will be four inches, thus leaving ample space for dumping. Each of the shafts 34 is adapted, as before described, for engagement by a crank whereby the bars may be oscillated and the same locking arrangement or one equivalent thereto may be used for preventing the grate bars from being accidentally turned to a dumping position when shaking the grate, this locking bar being shiftable so as to permit the grate bars being turned to a vertical position.

I have illustrated in connection with this grate another form of locking means in which the shafts 34 are provided with diametrically extending locking lugs or stops 36, and in which the locking means consist of two slidably mounted members 37 disposed side-by-side and longitudinally slotted at 38, each of these members being provided with teeth 39 engaged by a pinion 40, the shaft of which extends to the exterior of the furnace. By turning this shaft in one direction the members 37 will be shifted in one direction toward the shafts 34 and by turning the shaft in the opposite direction the shafts 34 will be

shifted in the opposite direction. One extremity of each member 37 is beveled as at 41 on its opposite faces; these beveled faces acting as stops limiting the movement of 5 lugs 36 so that the shaft can only make a quarter turn. By retracting these two sections 37 they may be withdrawn from their stopping position, and the grate bars may then be completely rotated.

10 In Fig. 3 I have illustrated another form of grate suitable for certain sizes of grates as will be later stated. This grate also embodies the same principle as the grates heretofore described and includes the rim 42 15 formed with the inwardly projecting lugs 43. This rim may be made in two sections, if desired, coacting with the rim are the two lateral shafts 44 and the middle shaft 45. The lateral shafts are formed with the lateral projecting lugs or arms 46 which interdigitate with the lugs 43 and the middle shaft 45 is provided with the lugs 47 which are disposed in staggered relation with the lugs 46 20 on the shaft 44. These lugs in an 18½ inch 25 grate are preferably three inches deep so that when the lugs are turned to a vertical position there will be ample space for the discharge of clinkers, unburned coal, etc. If the lugs are three inches in depth there will 30 be a space of three inches between the lugs when turned to a vertical position and if four inches in depth there will be a space of two inches.

It is to be noted that in all of these grates, 35 the grate bars are of such depth that they may be reversed when one surface of the bar is badly burned. The middle bar of a three-bar grate may, of course, be completely reversed as it stands, but the lateral bars of 40 a three-bar grate must be not only reversed, but interchanged with each other. In the two-bar grate the bars may be reversed and interchanged, but in this case they must also be turned end-for-end. The two-bar grate is 45 particularly designed for one size measuring less than 24 inches in diameter, thus fire pots measuring from 24 to 36 inches should have three bars and those measuring from 36 to 48 inches should have four grate bars or sections. 50 Because of the fact that the grate bars are particularly deep (three or four inches) a thorough shaking of the grate is possible through sections of the grate in which one section is stationary while the other is being 55 violently oscillated. In these circumstances the ashes, clinkers, or fuel are not likely to be caught and ground up because these sections which move back and forth are uniform in shape. Individual grates rotate partially 60 so as to accomplish this shaking and sifting movement. In some cases the reversibility of the grate sections is not possible, thus in all those fire pots which measure less than 24 inches in diameter, only two grate bars can 65 be installed because if three grate bars are

being made use of, either a perfect dumping action is lost or the function of reversing the center bar must be eliminated due to lack of necessary space.

In all the embodiments of my invention 70 which have been illustrated, it is to be noted that the size of the spaces or passages between the confronting faces of the lugs on the grate bars and on the rim remains the same. These 75 spaces must be proportioned in accordance with the cross sectional area of the flues and this is true whether the grates are large or small. It is an absolute requirement for a good and practical grate that it shall fulfill 80 the following requirements: First, that the right size of "mesh" or passageways between the confronting faces of the lugs be secured; that the airway be exactly in proportion to the area of the flue; that the overhang of the 85 lugs are in proportion to the general axis; that the grate bars are so constructed as to allow about four inches open space for dumping; that the grate shall have a depth of about four inches to provide for the reversing 90 of the grate bars, and that there shall be about three inches of movement for shaking.

All forms of the grates illustrated secure 95 the functions above stated with the exception of the grate reversing facility which, under some circumstances must be sacrificed. All 100 of the functions are secured by grates constructed in accordance with my invention in the following diameter of grates: 12 inches diameter having two bars, 24 inches diameter having three bars, and 36 inches diameter having four bars.

The grate reversing facility is sacrificed as to the center of the bar of a three bar grate with grates of the following sizes, namely 105 those which approximate 18 inches in diameter, those which approximate 30 inches in diameter, and those which approximate 40 inches in diameter.

As to the grate reversibility, it is obvious 110 that a grate having a diameter of eighteen inches would have to be fitted up either with two bars on which the lugs would be rather long, or when three bars were used, the depth of the grate would have to be reduced so as to secure a proper space between the confronting faces of the bars when the grate was dumped. In this case, therefore, where three bars are installed in a small grate and the depth correspondingly reduced, we sacrifice 115 reversibility and also sacrifice a trifle of the shaking ability.

On grates of the following diameters, 125 namely 12, 24, 36 and 48 inches, the depth of the grate bars is four inches and the space between the grate bars when they are turned to a vertical position for dumping is four inches; but in grates whose diameter is not divisible by four but only divisible by three, it is necessary that three grate bars be used and that the depth of the grate be reduced 130.

correspondingly in order to secure a proper distance or space between the lugs or grate bars when turned to a vertical position, and this prevents reversibility.

5 I have illustrated a number of grates constructed in accordance with my invention, and it will be understood that the principle of my invention may be applied to grates of many different sizes without departing 10 from the claims.

What I claim is—

1. In a grate, a rim formed in two opposed sections, a plurality of grate bars having parallel shafts rotatably mounted upon the 15 rim and extending at right angles to the line of separation between the sections of the rim, the shafts of the lateral grate bars being removable from engagement with the rim and interchangeable whereby the lateral grate 20 bars may be interchanged and reversed when one surface of the lateral section is burned out, the intermediate grate bar being completely reversible in the rim whereby when said grate bars have been burned out, on one 25 face, all the grate bars may be reversed.

2. In a grate, a frame, a plurality of grate bars having parallel shafts rotatably mounted in the frame, the grate bars having oppositely projecting lugs interdigitating when 30 disposed in approximately the same plane, the ends of said lugs being convexly rounded concentric to the axis of oscillation of the 35 grate bars whereby the ends of the lugs when the grate bars are oscillated through an arc not greater than the depth of the lugs, will be spaced from the shafts of adjacent grate bars the same distance at all times, the upper 40 and lower faces of the grate bars being flat.

3. In a grate, a rim, a plurality of grate 45 bars rockingly mounted upon the rim, the grate bars and rim having lugs interdigitating with each other when in normal position, the grate bars being oscillatable to a dumping position, and means for normally limiting 50 the oscillation of the grate bars to approximately ninety degrees comprising stop lugs projecting from each grate bar and a longitudinally shiftable member having upwardly and laterally extending stops thereon, one 55 for each grate bar, said member when shifted in one direction, bringing the stops into the path of movement of the lugs to thereby limit the movement of the lugs to an angular distance approximately not greater than ninety 60 degrees, or when shifted out of such position permitting the grate bars to be turned through an angle greater than 90°.

4. In a grate, a frame, a plurality of grate 65 bars rockingly mounted upon the frame, the 70 grate bars and frame having lugs interdigitating when disposed in the same plane, the grate bars being oscillatable to a dumping position, means for normally limiting the oscillation of the grate bars to approximately 75 90° comprising a radially projecting lug on

each grate bar, a manually shiftable member disposed to extend transversely of all of the several grate bars, that edge of the member adjacent the grate bar being cut away opposite each grate bar, each cut away portion having at one end a longitudinally extending lug spaced from the bottom of the cut away portion and acting as a stop, said member when shifted in one direction bringing the several stops into the path of movement of the several lugs and thereby limiting the movement of the lugs to said angular extent, said member when shifted in the other direction, permitting the grate bars to be turned through an angle greater than 90°.

In testimony whereof I hereunto affix my signature.

AUGUST J. KOEPSELL.
